UNITED STATES PATENT OFFICE.

STEPHEN R. KROM, OF PLAINFIELD, NEW JERSEY.

ORE-CRUSHER.

SPECIFICATION forming part of Letters Patent No. 330,408, dated November 17, 1885.

Application filed February 9, 1885. Serial No. 155,334. (No model.)

To all whom it may concern:

Be it known that I, STEPHEN R. KROM, of Plainfield, in the county of Union and State of New Jersey, have invented an Improvement in 5 Ore-Crushers, of which the following is a specification.

This invention relates to that class of ore-crushers in which there is a hopper between a stationary and a vibrating jaw, the latter jaw 10 being moved by a toggle. A crusher of this general character may be seen in my Patent No. 158,800.

The present improvements relate to the details of construction and to the combinations 15 of devices hereinafter set forth and claimed, whereby the crusher is more easily made and the parts are cheaper and better adapted to the intended uses.

In the drawings, Figure 1 is a section of the 20 crusher. Fig. 2 is an elevation. Fig. 3 is a plan view, and Fig. 4 is a side view, of one of the journal boxes.

The two side frames, A A, are of the configuration represented, and strengthened by 25 ribs. The stationary jaw B preferably rests at its lower edge upon brackets b b, that project from the ends of the side frames, but it may be supported by its bolts, and said jaw is held in place by the short bolts C, that 30 pass through the lugs C', cast on the side frames, A, and the long bolts E pass through lugs on the frames A and extend the whole length of the machine. The lower bolts, E, pass from end to end of the side frames, A, through the ends of the stationary jaw and 35 through the toggle-abutment F, that extends across from one frame to the other. The lugs E' upon the frames, near each end of the bolts E, are cast with such frames and strength- 40 en them, and the bolts, passing through such lugs, tie the parts together. The filling pieces or plates at g are introduced between the ends of the side frames, A, and the stationary jaw, so that as the surfaces of the stationary and 45 moving jaws wear away, one plate at a time, on each side is removed to allow the jaws to be screwed up to the regular width of delivery-opening. The moving jaw H is supported by and moves upon the rock-shaft I. It is made 50 as a heavily-ribbed shell with a ledge, h, for the movable face, composed of bars h' h² h³, to rest

upon. The jaw B is similarly made with a ledge, k, for the movable face-bars k' k² k³. The lower bars, h' k', will wear away the most rapidly, and are to be set out from time to 55 time as their surfaces wear away, and filling bars or plates are introduced behind them. The plates, h³ k³, are secured by bolts i, with conical heads passing into conical holes in the plates. These bolts must be loosened when 60 the other plates are to be set out or changed, and when they are tightened up their conical heads serve to force down the jaw-plates and clamp them firmly in place.

In consequence of the moving jaw swinging 65 upon a shaft that is placed below the crushing-surfaces there is less motion where the jaws are near to each other than there is where the jaws are farther apart; hence the crushed products are more uniform than in the crushers 70 where the jaw-axis is above the hopper, and a product is obtained that is much finer because the movement of the jaw at the delivery opening is comparatively slight and large pieces cannot escape. The driving-shaft L is 75 provided with a fly-wheel, L', and belt-pulley L'. The journal-bearings N upon the frame A are made to receive the eccentric-shaft L, each box o being made in two parts that encircle the journal, and these are bolted together at 80 3, and upon the sides of these boxes there are cylindrical trunnions r, upon which the boxes may swing. There are countersinks at the ends of the trunnions for receiving the screws 4 4, that enter from opposite sides 85 of the bearings N, and the frames A are recessed for the reception of the boxes o and their trunnions. The object of this construction is to allow a small amount of play to the boxes o within the bearings N, so that if the 90 shaft L springs under the heavy strain to which it is subjected the journal-boxes will move and not be cut or unevenly worn by the vibration or spring of the shaft. The eccentric portion of the shaft L between the bearing- 95 boxes receives the link P, which has at its lower end the bearing-blocks p for the toggle-bars q, one of which bears against the back of the moving crusher-jaw and the other against the toggle-abutment F. There is a rod, S, 100 from the moving jaw, passing through the toggle-abutment and provided with a spring, s',

and adjusting-nut, by which the necessary force is applied for drawing the jaw back and keeping the toggle-surfaces in contact. The cross-head forming the toggle-abutment F is recessed behind each nut *f* of the bolts E, and there are plates of wrought iron or steel, *v*, in the form of washers, that rest at their edges upon the head-block around the recesses, and the nuts bear upon these wrought iron or steel washers. The object in using these washers and recesses is that these washers are the weakest part and will spring or bend with undue pressure, instead of any other part of the crusher breaking, and these wrought washers are better than the breakable cups described in my former patents, because such breakable cups sometimes fracture under great strain, and the flying pieces are dangerous, whereas the wrought-metal washers do not fly to pieces, but may sometimes be turned around when they have become concaved and used over again. Besides, when brittle cups are used, generally, only one will break, and the other one remaining whole, the parts of the machine are twisted and sometimes bent. With flexible disks both sides will yield and each set of washers become bent. If the bend or set to the washers is small, the nuts can be set up and bring the parts to place without changing the washers. The filling plates *g* may also be placed between the ends of the frames and the toggle-abutment, so as to be removed from time to time and cause the moving jaw to approach the stationary jaw, and thereby compensate for wear in the parts. I also remark that the wrought-metal washer-plates *v* may rest at their edges upon rings projecting from the surface of the toggle-abutment and cast with such toggle-abutment or made of a separate piece.

I do not claim filling-plates introduced between the jaw-faces and backing of the jaw, as in this case to remove the plates it is necessary to take off the jaw-faces but by introducing the filling-plates between the ends of the frames and the end portions of the removable

jaw backing the filling-plates can be removed with facility.

I claim as my invention—

1. The combination, with the side frames, A, the toggle-abutment, and the moving and stationary jaws, of the short bolts C, passing through the stationary jaw and through lugs C', cast in the upper part of each frame at one end, and the long bolts E, passing through the stationary jaw, the toggle-abutment, and lugs on the frames A, substantially as set forth. 55

2. The combination, with the moving and stationary jaws in an ore-crusher, of the side frames, the separate filling-plates between the ends of the frames and the end portions at each side of the stationary jaw, and the tie-bolts passing through lugs cast on the frames A, substantially as set forth. 60

3. The combination, with the stationary and movable jaws, the toggle-bars *q*, link P, and bearing-block *p*, in an ore-crusher, of the driving eccentric-shaft L, the two-part journal-boxes *o*, having trunnions *r* at opposite sides of said boxes, and the side frames having the bearings N, recessed to receive the journal-boxes *o* and trunnions *r*, substantially as specified. 70

4. The combination, with the stationary and moving jaws, the side frames and side bolts, of the toggle-abutment formed with recesses, the wrought-metal washers resting at their edges around the recesses, the nuts, toggle-bars, eccentric-shaft, and link, substantially as set forth. 75

5. The combination, with the stationary and movable jaws having ledges at their lower portions, of the movable faces made of narrow horizontal bars and plates, and the devices, substantially as set forth, for securing such bars and plates in place, substantially as set forth. 85

Signed by me this 2d day of February, A. D. 1885.

STEPHEN R. KROM.
